UNITED STATES PATENT OFFICE.

BORUCH LAPKIN, OF TORONTO, ONTARIO, CANADA, ASSIGNOR TO BURT E. LLOYD, OF WOODCLIFF, NEW JERSEY.

EYE MOUNTING.

Application filed July 30, 1924. Serial No. 728,995.

This invention relates to doll's heads of the sleeping type in which the eyes are substantially spherical and are oscillated by means of a weight to expose or hide the pupil 5 depending on whether the doll is held in upright or in sleeping position.

Most of the arrangements heretofore devised for controlling the eyes are objectionable in that they do not operate properly if 10 the eyes or sockets are not exactly true in form, and their method of mounting is such that the operation of the eyes is affected by changes in the shape of the head due to weather conditions, the heads often being 15 made of material which is affected by heat, dampness, etc. Further trouble is also caused through children displacing the eyes with their fingers, and also through the support for the eyes becoming disconnected from 20 the head.

While other arrangements have been devised which will operate fairly satisfactory, these other arrangements have been so expensive to make that the cost of the doll is very 25 materially increased.

My object therefore is to devise an arrangement which will cost but very little, if any, more than the arrangements hereinbefore first referred to, but with which the eyes 30 will operate properly under all conditions, or if for any reason the eyes should stick, the condition may be easily remedied by a slight pushing inwardly of the eyes.

A further object is to provide a mounting 35 in which all the parts may be put together prior to the mounting in the head.

A still further object is to devise an improved construction whereby the eyes may be quickly and easily adjusted relative to 40 one another on their common support.

I attain my objects by means of the construction hereinafter described and illustrated in the accompanying drawings in which

Fig. 1 is a vertical section of a doll's head 45 showing my improved eye mounting therein;

Fig. 2 a front view of the eye mounting;

Fig. 3 a rear view of an eye; and

Fig. 4 a cross section on the line 4—4 in Fig. 3.

50 In the drawings like numerals of reference indicate corresponding parts in the different figures.

1 is a doll's head, which will be of ordinary construction and has an open top which is 55 covered by means of the hair in the usual

manner. Mounted in the head is the support 2 which may be secured in place in any desired manner, as by means of a bolt 3 passing through the top of the forehead. On the lower end of the support 2 are formed 60 bearings 4 for a shaft 5. A swinging link 6 has one end connected with this shaft.

On the other end of the swinging link is formed bearings 17 in which the bridge piece 7 is pivotally supported. On each 65 end of this bridge piece 7 is mounted an eye 8, which eyes, as usual, are of spherical form. To oscillate the eyes, the pendulum 9 is provided. In actual practice the head will, as common in the art, be molded from a 70 suitable material which is subsequently given a finishing coat of glue paint, and the support will as usual be secured in place prior to applying this finishing coat to the head. As the glue paint is likely to cause 75 the eyes to stick in the sockets, it is desirable that they be removed during the time the coating is being applied and setting, and I therefore preferably form the bearings 17 as hooks so that the bridge piece with the 80 eyes may be removed or replaced as desired.

Mounted on the shaft 5 is the spring 10, one end of which spring engages the rear side of the support 2 and the other end the back of the swinging link 6. This swinging 85 link, as will be seen from Fig. 1, is thus held in forward position with the eyes in place in their sockets. I also secure in place, by means of the screw 3, a member 18 adapted to limit the downward swing of the pendulum 9 when the doll is in sleeping position.

In practice the parts will all be assembled together before being placed in the doll's head, although, as suggested above, the bridge piece carrying the eyes, may be removed during the coating operation. It will be seen that the eyes may be pushed away from their sockets without danger of affecting their operation and that the spring 10 will return the parts to proper position with the eyes in the sockets. If for any reason the eyes should stick in their sockets, a slight pressure on the eyes will move them back sufficiently to allow them to swing and return to the proper position.

In order that the eyes 8 may be adjusted relative to one another and to the support, I mount them in the following manner. Each eye comprises a metal plate 11 on which is secured a hemispherical metal shell 110

12, over which shell is placed a celluloid shell 13 on which appears the representation of the eye.

At each side of the plate, and preferably integral therewith, is formed a lug 14, which lugs are bent back, as will be seen particularly on reference to Fig. 4, to form clamping members between which are received the U-shaped member 15 in which is received one end of the bridge piece 7.

Holes are formed in the clamping members 14 and in each leg of the member 15 for the passage of a bolt 15, which has a nut set up thereon. By suitably tightening up the nut on the bolt, the clamping members 14 and the legs of the member 15 are drawn together to frictionally engage one another to prevent movement of the member 15 relative to the clamping members and also to prevent movement of the member 15 both rotarily and longitudinally of the cross piece.

Preferably the plate 11 is grooved longitudinally of the bridge piece 7, and the bottom of the groove is cut away at the ends as shown in Fig. 3.

It will thus be seen that by simply loosening the nut on the bolt 15, the position of the eye may be varied as desired, viz, longitudinally or rotarily of the bridge piece 7, and may be set at any desired angle to the longitudinal axis of the bridge piece.

From the above description it will be seen that I have devised a construction which will satisfactorily attain the objects of my invention as set out in the preamble of this specification.

What I claim is:—

1. In a sleeping doll's head, the combination of a support mounted therein; a link hingedly connected with said support; eyes pivotally carried by the said link; a resilient member tending to rock said swinging link on its hinge to position the eyes in their sockets; and a weight for actuating said eyes.

2. In a sleeping doll's head, the combination of a support mounted therein; a link hingedly connected with said support; eyes pivotally carried by said link; and a spring engaging said support and link and tending to rock said link on its hinge to position the eyes in their sockets; and a weight for actuating said eyes.

3. In a sleeping doll's head, the combination of a support mounted therein; a swinging link pivoted on the support; a cross piece pivotally and releasably carried by the swinging link; an eye on each end of said cross piece; a resilient member tending to hold said swinging link with the eyes in position in their sockets; and a weight for actuating said eyes.

4. In a sleeping doll's head, the combination of a support mounted therein; bearing means on said support; a shaft carried by

said bearing means; a swinging link carried by said shaft; eyes carried by the said link; a spring on said shaft, one end of said spring engaging the support and the other end the link, and tending to hold the latter with the eyes in position in their sockets; and a weight for actuating said eyes.

5. In a sleeping doll's head, the combination of a support mounted therein; a swinging link pivoted on the support; a cross piece pivotally carried by the swinging link; an eye on each end of said cross piece; a resilient member tending to hold said swinging link with the eyes in position in their sockets; and a weight for actuating said eyes.

6. An eye for dolls and the like comprising a plate; a hemispherical shell carried by said plate, a pair of clamping members on said plate extending upwardly therefrom; a member extending downwardly toward said plate and rotatably mounted between said clamping members and adapted to receive the end of a bridge piece of a pair of eyes, said member being rotatable relative to the clamping members; and means for actuating the clamping members to frictionally engage the last mentioned member, to hold it from rotation.

7. An eye for dolls and the like comprising a plate; a hemispherical shell carried by said plate, a pair of clamping members on said plate; a U-shaped member adapted to be received between said clamping members and adapted to receive the end of a bridge piece of a pair of eyes; and means for actuating the clamping members to frictionally engage the U-shaped member and to actuate the legs of the U-shaped member to frictionally engage the bridge piece.

8. An eye for dolls and the like comprising a plate; a hemispherical shell carried by said plate, a pair of clamping members on said plate; a U-shaped member adapted to be received between said clamping members and adapted to receive the end of a bridge piece of a pair of eyes, said clamping members and U-shaped members having aligned holes therethrough and a bolt passing through said holes to actuate the clamping members to frictionally engage the U-shaped member and to actuate the legs of the U-shaped member to frictionally engage the bridge piece.

9. In a sleeping doll's head, the combination of a support mounted therein; a swinging link pivoted on the support, said swinging link having a hook formed thereon; a cross piece pivotally and releasably mounted in said hook; an eye on each end of said cross piece; a resilient member tending to hold said swinging link with the eyes in position in their sockets; and a weight for actuating said eyes.

10. In an eye mounting for dolls and the

- like a frame; a pair of clamping members on said frame; a U-shaped member adapted to be received between said clamping members and adapted to receive the end of a bridge piece and means for actuating the clamping members to frictionally engage the U-shaped member and to actuate the legs of the U-shaped member to frictionally engage the bridge piece.
11. In an eye mounting for dolls and the like a frame; a pair of clamping members on said frame; a U-shaped member adapted to be received between said clamping members and adapted to receive the end of a bridge piece, said clamping members and U-shaped members having alined holes therethrough and a bolt passing through said holes to actuate the clamping members to frictionally engage the U-shaped member and to actuate the legs of the U-shaped member to frictionally engage the bridge piece.
12. In an eye mounting for dolls and the like a frame; an upwardly extending lug on said frame; a member adapted to receive the end of a bridge piece, said member extending 25 downwardly and carrying said bridge piece, said lug and member being rotatable relative to one another; and means for clamping said lug and member together to prevent rotation.
13. In an eye mounting for dolls and the like a frame; a pair of upwardly extending lugs on said frame; a downwardly extending supporting member between said lugs and adapted to receive the end of a bridge piece, 35 said lugs and member being rotatable relative to one another; and means for clamping said lugs and member together to prevent rotation.

Signed at Toronto, Canada, this 7th day 40
of July 1924.

BORUCH LAPKIN.
